COLLAPSIBLE FURNITURE

Edward P. La Kaff, Chicago, Ill.

Application July 18, 1950, Serial No. 174,449

8 Claims. (Cl. 5—116)

1

This invention relates to collapsible furniture such as cots, stools, chairs, and the like wherein a pair of generally U-shaped frames pivoted together in staggered overlapped relation at the mid-points of their end portions have angularly extending legs on their end portions to form support legs and wherein sheet material, preferably in the form of a tube or endless loop, is mounted on the side legs of the U-shaped frames.

The invention specifically relates to a collapsible cot especially suitable for day nurseries and the like and having an easily stacked, collapsed position and an opened up reinforced rigid position, wherein the end portion of one U-shaped member overlies the knee of the supporting leg of the other U-shaped member at diagonally opposite corners of the cot.

The invention will be hereinafter specifically described as embodied in a collapsible cot, but it should be understood that the principles of this invention are generally applicable to collapsible furniture and the invention is therefore not limited to the herein disclosed preferred embodiment.

In accordance with the invention, a pair of metal tubes are bent into generally U-shape with angularly extending legs on the end portions of the U. These legs are connected through a rounded knee with the end portions of the U. The two frame pieces are pivoted together at the mid-points of their end portions in staggered relation with one end portion of one frame lying within the adjacent end portion of the other frame and the other end portion of said one frame lying outside of the adjacent end portion of the other frame. The end portions are therefore in side by side relation with each frame having an outside end portion as well as an inside end portion. The light portions of the U-shaped frames receive thereover a tubular sheeting such as a canvas band to form the bed portion of the cot. When the frames are opened up to move the light portions apart, the canvas band will be positioned in a horizontal plane and the bight portion of one frame will overlap the knee of the other frame at diagonally opposite portions of the cot to provide a rigid support. When the bight portions are moved together, the supporting legs will extend in opposite directions to carry the collapsed cot in an upright position. The band or tubular sheet can be easily slipped on and off of the collapsed frame.

It is, then, an object of this invention to provide collapsible furniture composed of pivoted together

2

U-shaped members arranged so as to form a rigid frame overlapped at diagonally opposite corners when in opened up position.

Another object of the invention is to provide collapsible furniture composed of pivoted together U-shaped tubular frames with offset leg defining extensions joined thereto through rounded knees, wherein one frame overlies the knee of the other frame at diagonally opposite corners of the assembly when the assembly is opened up for use.

Another object of the invention is to provide a collapsible cot composed of two U-shaped pivoted together frames and an easily removable tubular sheet.

Another object of the invention is to provide a collapsible cot especially suitable for day nursery and the like usage wherein staggered pivoted together U-shaped frames removably carry a tubular sheet and are easily swung from collapsed upright self-supporting position to opened up rigid position.

Other and further objects of the invention will be apparent to those skilled in the art from the following detailed description of the annexed sheet of drawings, which, by way of a preferred example only, illustrates one embodiment of the invention.

On the drawings:

Figure 1 is a perspective view of the cot of this invention in open position.

Figure 2 is a perspective view of the cot in collapsed position.

Figure 3 is a top plan view of the cot in open position.

Figure 4 is an end view of the cot in open position.

Figure 5 is a top plan view of the cot in collapsed position.

Figure 6 is an end view of the cot in collapsed position.

As shown on the drawings:

As best shown in the perspective view of Figure 1, the cot 10 is composed of two generally U-shaped tubular metal frames 11 and 12, a tubular or endless band canvas sheet 13, and pivot studs 14, 14. The frame 11 has an elongated bight portion 11a, end portions 11b, 11b extending in the same plane and in the same direction from the bight portion 11a, and offset support legs 11c on the ends of the end portions 11b and joined therewith through a rounded knee portion 11d. The frame 12 has an identical bight portion 12a, end portions 12b, support legs 12c, and knees 12d. Rubber pads P are mounted on the ends of the legs.

The pivot studs or bolts 14 connect the frames 11 and 12 in staggered relation at the mid-points of the end portions 11b and 12b thereof. Thus, the end portions 11b and 12b are in side by side relation with one end portion 11b on the outside of the adjacent end portion 12b, while the other portion 11b is on the inside of the adjacent end portion 12b.

When the cot 10 is opened up as shown in Figure 1, one end of the bight portion 11a of the frame 11 overlies and rests upon one knee 12d of the frame 12 at one corner of the assembly, while at the opposite diagonal corner of the assembly the bight portion 12a of the frame 12 overlies and rests upon the knee 11d of the frame 11. The cot is thereby supported at diagonally opposite points A and B directly above the legs 12c and 11c respectively.

The legs 11c and 12c diverge slightly outward from the end portions 11b and 12b respectively in obtuse angular relation therewith.

As shown in Figure 2, when the cot 10 is in collapsed position, the bight portions 11a and 12a are moved together and the sheet 13 hangs in a loose loop. The legs 11c and 12c extend in opposite directions so that their outer faces form supports for the collapsed cot. In this position the band or tube 13 can easily be removed from and mounted on the collapsed frame.

Figures 3 to 6 further illustrate the manner in which the U-shaped frames 11 and 12 cooperate in open and in closed position, and show the points of support A and B in the open position as well as the manner in which the sides of the legs form supports for the collapsed position of the cot.

The assembly of this invention is inexpensive, easy to manipulate, rigid when in opened up position, compact when in collapsed position, and includes an easily removable and washable sheeting to form the bed support surface.

It will be understood that modifications and variations may be effected without departing from the scope of the novel concepts of the present invention.

I claim as my invention:

1. A collapsible article of furniture, comprising a pair of U-shaped frames each having a bight portion, two end portions connected to the ends of the bight portion and extending in substantially the same direction and plane, and a leg portion on each of the end portions, means for pivoting the respective end portions of one frame to the respective end portions of the other frame in side-by-side adjacent relation, one end portion of one frame being inside the adjacent end portion of the other frame, and the other end portion of said one frame being outside the adjacent end portion of the other frame, the bight portion of said one frame in open position resting upon one of the adjacent end portions of said other frame and the bight portion of said other frame resting upon one of the adjacent end portions of said one frame, and a tube of flexible sheet material surrounding both bight portions, said tube being a support surface when the bight portions are in open position and being removable by passing over the end portions and leg portions when the bight portions are moved together.

2. A collapsible article of furniture comprising a pair of U-shaped frames each having a bight portion, two end portions extending in the same direction and plane from the bight portion, and two leg portions extending angularly to the plane of said bight portion and two end portions and

each connected to one of said end portions, means for pivoting the respective end portions of one frame to the respective end portions of the other frame in side-by-side relation, one end portion of one frame being between the end portions of the other frame and the opposite end portion of said one frame being outside the end portions of said other frame, the bight portion of said one frame resting upon one of the end portions of said other frame, and the bight portion of said other frame resting upon one of the end portions of said one frame in open, non-collapsed position of the frames.

3. A collapsible article of furniture comprising U-shaped tubular metal frames having bight portions and end portions extending in the same direction and in the same plane and offset legs extending in obtuse angular relationship to the end portions, means pivoting the end portions together in side-by-side relation at substantially the mid-points thereof with one end portion of one frame lying outside the end portions of the other frame and with the other end portion of said one frame lying inside the end portions of the other frame, whereby when said frames are opened up the bight portions will overlie and rest upon the end portions at diagonally opposite corners adjacent the offset legs and when said frame is in collapsed position said offset legs will hold the bight portions in side-by-side relation.

4. A collapsible cot comprising a pair of tubular metal U-shaped frames, each frame having a bight portion, a pair of end portions extending in the same direction and in the same plane and offset leg portions in obtuse angular relationship to the end portions, means pivoting the end portions together in side-by-side relation at the mid-points thereof, one end portion of one frame lying within the other frame at one end of the assembly and the other end portion of said one frame lying outside said other frame at the other end of the assembly, said offset leg portions being joined with said end portions along rounded knee areas, the bight portion of said one frame overlying the knee area of said other frame at said other end of the assembly when the cot is in open position, and the bight portion of said other frame overlying the end portion of said one frame at said one end of the assembly, the offset leg portions having ends forming feed for the cot in open position, said offset leg portions having side surfaces forming supports for the cot in collapsed position, and a tubular sheet mounted on the bight portions to form the support surface for the cot in open position and being removable over the end portions when the frame is in collapsed position.

5. A collapsible cot comprising a pair of U-shaped frames having end portions pivoted together at the mid-points thereof and each frame having an end portion within the other frame and an end portion outside the other frame, an offset leg on the end of each end portion extending generally at right angles thereto, said legs forming substantially upright supports for the frames when the end portions are swung into a horizontal plane and forming laterally extending supports when the end portions are swung into a vertical plane, and sheet material on said frames forming a support surface.

6. A collapsible article of furniture, comprising a pair of U-shaped frames each having a bight portion, two end portions connected to the bight portion and a leg portion on each of the end portions, means for pivoting the respec-

tive end portions of one frame to the respective end portions of the other frame in side-by-side adjacent relation, one end portion of one frame being inside the adjacent end portion of the other frame at the pivoting means thereof, and the other end portion of said one frame being outside the adjacent end portion of the other frame at the pivoting means thereof, the bight portion of said one frame in open position of the article resting upon at least one of the end portions of 10 said other frame and the bight portion of said other frame resting upon at least one of the end portions of said one frame, and a tube of flexible sheet material surrounding both bight portions, said tube being a support surface when the bight 15 portions are in open position and being removable by passing over the end portions and leg portions when the bight portions are moved together.

7. A collapsible article of furniture, comprising a pair of U-shaped frames each having a bight portion, two end portions connected to the bight portion and a leg portion on each of the end portions, means for pivoting the respective end portions of one frame to the respective 20 end portions of the other frame in side-by-side adjacent relation, one end portion of one frame being inside the adjacent end portion of the other frame at the pivoting means thereof, and the other end portion of said one frame being outside the adjacent end portion of the other frame at the pivoting means thereof, and the bight portion of said one frame in open position of the article resting upon at least one of the end 25

15

30

portions of said other frame and the bight portion of said other frame resting upon at least one of the end portions of said one frame.

8. A furniture article comprising: a pair of generally U-shaped frames having generally parallel bight portions together defining a support and having transverse end portions pivotally connected for relative pivotal movement of said frames about an axis generally parallel to and equally spaced from said bight portions, each of said end portions having means arranged for projecting in a direction angularly related to a plane through said bight portions when they are in open position for contacting a support surface to space said bight portions therefrom, and at least one end portion of each frame engaging and supporting a part of the other frame in operative position of the article.
